UNITED STATES PATENT OFFICE.

FREEMAN VALENTINE WALKER, OF BLUFFTON, SOUTH CAROLINA.

SIGN OR DISPLAY-CARD.

1,089,996.

Specification of Letters Patent. Patented Mar. 10, 1914.

Application filed June 7, 1912. Serial No. 702,305.

To all whom it may concern:

Be it known that I, FREEMAN V. WALKER, a citizen of the United States, residing at Bluffton, in the county of Beaufort and 5 State of South Carolina, have invented new and useful Improvements in Signs or Display-Cards, of which the following is a specification.

This invention relates to a sign or display 10 card adapted to be used in the ordinary way or as a transparency and comprises essentially a perforate body of pasteboard, wood, wire or metal presenting a plurality of holes and having thereover a normally imperforate sheet of thin opaque paper or analogous material.

The object of the invention is to provide a simple and effective means for producing a sign in the form of letters or an indicating 20 illustration or advertising matter, or to construct a transparency design or face at the will of the user in such manner that light or a colored backing may be exposed therethrough and involving an organization that 25 will permit an extensive variation in letter forms, ornamentations or devices by a simple operation and at a comparatively small expense.

In the drawings: Figure 1 is an elevation, 30 partially broken away, of a device embodying the features of the invention and showing the manner of puncturing the same to form letters of the alphabet in spelling words and constructing signs. Fig. 2 is a 35 transverse vertical section on the line 2—2, Fig. 1, showing portions of the covering sheets released. Fig. 3 is a view similar to Fig. 1 looking at the back portion of the 40 card or sign device and illustrating a modification. Fig. 4 is a transverse vertical section on the line 4—4, Fig. 3.

The numeral 5, Fig. 1, designates a body or substructure which is shown in this figure as composed of an open mesh wire 45 fabric, and this fabric may be of any size and the meshes either large or small or of any dimensions between maximum and minimum size in accordance with the character of the letters or designs to be formed or of 50 the general proportions of the card or sign embodying the features of the invention. The said body is cut from wire fabric having meshes of different dimensions as found in the market and without requiring a particular preparation of the body or sub-

structure for the purposes of the invention. Instead of the wire mesh body or substructure 5, the latter may be composed of a sheet 6 of metal, wood or cardboard having perforations 7 formed therein at regular or 60 predetermined intervals, as shown by Fig. 3. It will therefore be understood that the body or substructure 5 or 6 may be of any material, it being only necessary to use a body having perforations or openings 65 therein at regular distances apart or arranged in regular order. Though not actually necessary to the success of the improved sign or display card, it is preferred that the openings or apertures in the body or substructure 5 or 6 be arranged in straight 70 lines at angles to each other. Over the body or substructure as thus explained a covering 8 is applied and secured to at least one side thereof, and said covering consists of a thin 75 sheet of opaque paper or analogous material that may be punctured or wherein openings may be formed in those portions thereof extending over the openings of the body or substructure 5 or 6. A second inclosing 80 covering 9, which may in like manner be a thin sheet of opaque paper or other readily puncturable material, may be applied to and secured against the opposite side of the body or substructure, and in some instances this 85 additional covering 9 may be of a colored paper or it may be a tinted or colored transparent paper which will permit light to pass therethrough and produce a pleasing effect when the opposite or outer covering 8 is 90 punctured to form the sign or design desired to be presented by the improved device. It is also intended that the sign or card be used as a part of the transparency 95 wherein a colored screen or other analogous device may be disposed back of the card or puncture device as common in transparency structures to produce an attractive appearance and pleasing illumination. When the 100 coverings 8 and 9 are both of opaque material they are simultaneously punctured, or the openings forming the letters as at 10, see Fig. 1, are produced in both coverings. By this means a sign or display card of greater thickness is produced and such double covering will give the sign or card 105 greater durability. In securing the coverings 8 and 9 to the body or substructure 5, any suitable adhesive material may be used, or in some instances the device as a whole 110

may be disposed in a frame after the manner of display signs and cards as now commonly constructed and whereby the opaque covering will be held in place against the perforate body or substructure. The body or substructure 6, as shown by Fig. 3, is also provided with a covering 11 of thin opaque material, such as paper, and the same convenience in forming letters, ornamentations or designs generally is permissible by the structure shown by Figs. 3 and 4 as in the structure shown by Figs. 1 and 2.

It will be understood that the opaque covering applied to the body or substructure in either form shown will be normally imperforate or unbroken, and the openings in the body or substructure will serve solely as the guide means for the punctures in producing letters, characters or designs in the sign or card, and in forming the punctures a pencil, pointed stick or metal punch may be used, each puncture being preferably located in the center of the wire mesh body or substructure 5, for instance, as shown by Fig. 1, or made of equal size with the openings or apertures 7 in the sheet body or substructure 6, as shown by Fig. 3. The size of the openings punched in the opaque covering, however, will be controlled by the will of the operator or user of the improved device.

From the foregoing it will be understood that it is the purpose of the invention to furnish a material for signs which may be either in the form of cards or in rolls and capable of being readily employed to produce a neat sign of any size. The mesh structure or arrangement of the body or the perforations in the latter serve as guide means in the formation of letters or designs and particularly provide a resistance to prevent tearing of the opaque covering or for preventing the said covering from being torn through from one opening to another in making the punctures in addition to the guide provided by the regular formation of the meshes or openings in the body to insure

the easy production of the openings of equal size and proportion in the opaque covering.

What is claimed is:

1. A blank for a sign or display device, comprising a perforate substructure, and a normally imperforate and unbroken opaque thin covering sheet of paper applied and secured directly against the said perforated substructure and adapted to be punctured to form letters and design configurations, the substructure at its edges terminating coincidently with the edges of the covering.

2. A blank for a sign or display device, comprising a perforate substructure composed of elements extending at right angles to each other, and a normally imperforate and unbroken opaque thin covering sheet of paper secured directly against and bearing upon the said substructure and closely fitting into the perforations in the latter, the said covering sheet of paper adapted to be punctured to form letters and designs, the substructure at its edges terminating coincidently with the edges of the covering.

3. A blank for a sign or display device, comprising a perforate substructure, and normally imperforate thin sheet paper coverings applied to opposite sides of the substructure and directly against the latter without interposed layers of any material, the covering sheets being drawn taut on the substructure and closely fitting in the openings in the latter and tightly bearing against the margins of the perforations of the substructure, the thin sheet paper coverings being adapted to be punctured to form letters and designs, the substructure at its edges terminating coincidently with the edges of the covering.

In testimony whereof I have hereunto set my hand in presence of two subscribing witnesses.

FREEMAN VALENTINE WALKER.
